UNITED STATES PATENT OFFICE.

HENRY ADAMS, OF STAMFORD, CONNECTICUT, ASSIGNOR TO THE ADAMS MINING MACHINERY CORPORATION, OF NEW LONDON, CONNECTICUT, A CORPORATION OF NEW YORK.

CENTRIFUGAL CRUSHER AND SEPARATOR.

1,197,888.

Specification of Letters Patent. Patented Sept. 12, 1916.

Application filed January 28, 1915. Serial No. 4,894.

To all whom it may concern:

Be it known that I, HENRY ADAMS, a citizen of the United States, residing at Stamford, in the county of Fairfield and State of Connecticut, have invented certain new and useful Improvements in Centrifugal Crushers and Separators; and I do declare the following to be a full, clear, and exact description of the invention, such as will enable others skilled in the art to which it appertains to make and use the same.

This invention relates to improvements in centrifugal crushers and separators and more especially for crushers of friable minerals and ores, particularly for anthracite coal where the least amount of fines or pulverized product is desired as the result of a single operation.

The primary object of the invention is to provide an apparatus of this character which may be simply and inexpensively constructed and which will effectively perform the functions for which it is designed.

Another object of the invention is to provide an apparatus which will not only break and crush the material treated but will automatically classify it after it is broken.

Another object is to provide an apparatus in which one blow only is struck on one side of the material at one time and which never subjects any one piece of material at the same time to a crushing force on opposite sides thereof; nor permits two pieces to strike against each other, thereby eliminating the formation of fines or pulverized product and retaining the structural strength of the material treated.

Another object is to provide an apparatus in which the material after being struck on an anvil and broken will drop on an adjustably mounted angle plate which is placed around the face of the anvil just below the point where the material will strike the anvil, after it leaves the revolving table and is thereby directed into suitable places of deposit.

With these and other objects in view, the invention consists of certain novel features of construction, and the combination and arrangement of parts as will be more fully described and claimed.

In the accompanying drawing is shown a vertical central section of the apparatus.

In the embodiment illustrated, this apparatus as shown, is designed for friable min-

erals and ores and more especially for anthracite coal and it may be worked either as a single unit or disposed one beside the other or one on top of the other, the number of machines used in the last instance, depending upon the degree of fineness to which it is desired to crush the material.

This apparatus comprises a revolvable table 1 which is here shown fixed to a shaft 2 driven by a pulley 3 from any suitable source of power. The shaft 2 is here shown mounted in suitable bearings 4 and 5 and the table 1 may be provided on its material receiving face with radial corrugations 6 if desired, depending on the material to be treated, in some instances it being desirable to omit these corrugations, and provide a plane surface for the table. An anvil 7 surrounds this table 1 and is here shown annular with the striking face 8 thereof, which is arranged opposite the periphery of the table 1, being shown perpendicular and in a plane at right angles to said table. The distance this striking face 8 is disposed from the periphery of the table may be varied, depending on the material to be treated. As shown, this annular anvil 7 is mounted on wheels 9 which travel on a circular track 10 and said anvil may be revolved by any suitable means (not shown) either in the same direction or in an opposite direction to the line of travel of the revolving table 1. The striking face 8 of this anvil may be plane, corrugated or toothed as desired, depending on the material to be treated.

Disposed around the inner face of the anvil with its top positioned just below its striking face 8, is a circular adjustably mounted guide plate 11 which may be supported in any suitable or desired manner and which inclines downwardly and outwardly from its upper toward its inner edge to receive and direct the material after it strikes the face 8 of the anvil, so that it will be guided into suitable bins below as will be hereinafter described.

The coal, coal and bone mixed, slate and rock, are all of different weights and hence, they will slide down the guide plate 11 with a velocity proportionate to their frictional resistance and the hoppers that are placed below the guide plate are positioned so that each piece of material will fall into its proper hopper. This guide plate 11 may be

adjusted up and down on the anvil 7 by any suitable means, turn buckles 12 being here shown provided for this purpose but any other means may be employed which will operate to vary the vertical position relative to the anvil to position it at the desired point thereon relative to the striking face thereof.

The turn buckles 12 connect the two rod sections 12' and 12'' and are designed to vary the length of the connecting rod 12^a, of which they form a part. One end of each rod 12^a is connected with the plate 11 and the other end with one of a vertically disposed series of spaced apertures 8' formed in the face 8 of the anvil 6 provided for the vertical adjustment of said plate 11.

Disposed around and inside of the anvil 7 at points spaced therefrom, are a plurality of spaced circular hopper-like members 13, 14, 15 and 16 which are placed in suitable position to receive the broken material when it falls from the guide plate 11 and which operate to direct the material into suitable receiving bins 17 arranged below said hoppers, whereby the material is automatically classified, proportionately to its frictional resistance, the lighter going farther than the heavier. The heavier particles meet with greater resistance and hence move at a slower speed and consequently fall into the hopper 16 which is disposed directly below the edge of the plate 11 and which passes it on into the bin below it and the smaller pieces according to their size and weight will be directed into the other hoppers, the heavier pieces traveling less distance than the lighter.

The heavier impurities, such as slate, bone and rock and other foreign matter which will not break on striking the anvil or, if broken, will be in large pieces, will have a greater angle of rebound than the material crushed and will consequently fall farther down and be directed into a bin 18 positioned to receive such waste and thus automatically separate it from the coal or other material being treated, leaving the latter in a pure unadulterated state. In the apparatus shown, four receiving bins and directing hoppers therefor are employed but it is obvious that any desired number may be used.

The guide plate 11 is designed to prevent the coal or other material after it has been broken by the anvil 7, from contacting with each other and from receiving a crushing blow from any other means and direct it into the hoppers with the least possible breaking force to eliminate as far as possible, the production of fines and pulverized material. The moment the coal is broken on the anvil 8, it falls onto the guide plate 11 and the pieces are immediately carried away. The next piece of coal that is broken on the anvil at the same place where the

first piece struck, strikes the anvil later than the first piece and as these pieces fall on the guide plate 11, they will not strike the first pieces which have already been carried away. One of the essential features of this 7 machine is that after a piece of material is struck and broken on the anvil, it is immediately carried away and not subjected to any further crushing or breaking force of any kind.

In this apparatus, it will be obvious that an outlet is provided around the entire machine between the discharging peripheral edge of the table 1 and the anvil 7, in order that each piece of material after it strikes the anvil absolutely leaves the machine without being subjected in any way to any further crushing force, such as would occur if this continuous outlet were not provided and hence, the main object of the apparatus will be accomplished, which is to prevent the material from receiving more than one blow on one side thereof and to prevent two or more pieces from striking against each other.

In the operation of this apparatus, coal or other material to be treated is fed to the upper face of the table 1 near the center thereof by any suitable feeding means (not shown) and said coal is carried outward to the periphery of the table by centrifugal action and is thrown off the table in a radial direction, striking the face 8 of the anvil just above the guide plate 11 and onto which the broken pieces fall and are directed into the respective hoppers and conveyed thereby into the classifying bins arranged below them.

As the material is fed on the revolving table, the centrifugal action carries it to the periphery and the material being fed onto said table with a regular feed, only one piece will leave the periphery at one point and this piece strikes the anvil nearly opposite the place where it leaves the periphery of the table. The next piece striking the anvil at that point will strike it later than the first piece mentioned and so on. As the material breaks on the anvil, it falls onto the guide plate 11 by which it is immediately conveyed to the bin designed to receive it. As this guide plate 11 is disposed at an angle sloping downward, the material is classified on this plate according to the frictional resistance afforded by the plate. It is obvious that as the broken pieces are immediately carried away on this plate, those falling from the anvil will not strike or fall on top of each other.

As above described, the angle of rebound of the foreign pieces or impurities, such as hammer heads and the like, which do not break on coming in contact with the anvil face 8 or break only in large pieces, will thus be caused to follow a line of travel which is farther down and outward than any of

the hoppers and consequently, will be directed into the bin 18 arranged to receive it.

The hopper-like members 13, 14, 15 and 16 are here shown of different heights, the 5 innermost member being lower than the others and the others gradually increasing in height toward the outermost member 16 to readily receive the different sized pieces of material discharged from the guide plate.

10 I claim:—

In a centrifugal crusher the combination of a revolute member for receiving the material to be treated, an anvil disposed oppo-

site said member and spaced therefrom, an angularly disposed guide arranged adjacent 15 the point on said anvil against which the material strikes when thrown off from said revolute member, and means for varying the position of said guide.

In testimony whereof I have hereunto set 20 my hand in presence of two subscribing witnesses.

HENRY ADAMS.
